SPINNING MACHINES

Walter Leutert, Geneva, Switzerland, assignor to Brematex, a society of Tangiers

Application June 29, 1955, Serial No. 518,824

Claims priority, application Luxembourg July 7, 1954

3 Claims. (Cl. 57—110)

The present invention relates to spinning machines including a ring rail and retractable yarn guides, the term "spinning machine" being meant to designate all textile machines including a plurality of spindles for the formation of cops, whether said machines are used for spinning proper or for any other operation of the same kind, such for instance as twisting. This invention is more especially but not exclusively concerned with spinning machines in which the spindles are directly driven and in particular driven by means of worms and worm wheels.

It has already been suggested, in machines of this kind, to dispose above every spindle a yarn guide mounted at the end of an arm which is normally in horizontal position, said arm being adapted to be lifted when so desired to permit of retracting the yarn guides when it is desired to remove the cops.

However, this operation had to be performed manually and this involved a loss of time. Furthermore, if the operator forgot to return the yarn guide into working position when restarting the machine, there were serious risks of breaking the yarn.

The object of the present invention is to provide a machine of the above mentioned kind which is better adapted to meet the requirements of practice than those used up to the present time.

The present invention relates to spinning machines having a ring rail which is adapted to have, below its normal lowest position, a complementary stroke called "underwinding stroke" corresponding to the formation, on the base of the cop, of some supplementary turns of yarn intended to be unwound when the cop is removed from the spindle on which it was mounted. The present invention consists essentially in mounting the yarn guides at the ends of retractable arms mounted on a support which moves together with the ring rail and in providing means adapted to cooperate with said arms so as to retract the yarn guides at the beginning of the underwinding stroke of the ring rail.

Preferred embodiments of the present invention will be hereinafter described with reference to the accompanying drawings, given merely by way of example and in which:

Fig. 1 is a sectional view on the line I—I of Fig. 2, showing an embodiment of the device according to the present invention.

Fig. 2 is a side view corresponding to Fig. 1.

Fig. 3 is a sectional view on the line III—III of Fig. 2.

Figs. 4 and 5 are views similar to Figs. 1 and 2 respectively, the yarn guides being shown in retracted position.

The embodiment of this invention shown by the drawing is supposed to be applied to a spinning machine which may be of any suitable type. For instance, it includes two rows of spindles 1 disposed in staggered fashion and driven by a shaft extending between these

2

two rows of spindles and carrying a plurality of worms which drive worm wheels carried by the spindles.

This spinning machine includes a ring rail *r* which is controlled in conventional fashion so that it can have below its lowest normal position an underwinding supplementary stroke intended to bring it below this lowest normal position.

The spinning machine further includes, in line with every spindle 1, a yarn guide 2 disposed at the end of a retractable arm 3 mounted on a support 4 (which may be constituted by an inverted U-shaped iron running along the whole length of the corresponding ring rail). Every arm 3 is pivoted about an axis 5 and extends horizontally transversely to support 4 when the yarn guide 2 is in line with the corresponding spindle 1.

Support 4 participates in the vertical movements of the ring rail and, for instance, there is one support 4 for every section of the spinning machine, two successive supports 4 being connected together by a sleeve 6 slideable on a fixed column 7 of the machine. Sleeve 6 is connected to the ring rail so that it participates in the vertical movements thereof.

According to my invention, I provide, in cooperation with arms 3, control means adapted to work when the ring rail is starting on its supplementary underwinding stroke to bring the yarn guides into retracted position.

Thus, when the underwinding operation is finished, all the yarn guides 2 have been automatically and simultaneously retracted.

Advantageously, the above mentioned means include fixed abutments carried by the frame of the machine and movable cooperating abutments participating in the vertical movements of support 4 but slidably guided with respect to said support so as to pivot arms 3 upwardly. In the construction illustrated by the drawings, the last mentioned movable elements consist of side bars 8 disposed on either side of support 4 and vertically guided with respect thereto so as to be able to move upwardly with respect to said support. For instance, said side bars 8 have horizontal extensions 9 which normally rest upon support 4.

Along the path of side bars 8 during the underwinding vertical displacement of the ring rail are provided fixed abutments 10 carried by the frame of the machine and positioned so that they cause said side bars 8 to move upwardly with respect to support 4 when the ring rail is moving down in the course of said underwinding stroke.

Figs. 4 and 5 show the relative positions occupied by the parts of the machine when the ring rail is reaching the end of its downward underwinding stroke.

It should be noted that, advantageously, arms 3 are extending obliquely for this position so that the mere action of gravity is sufficient to return them into horizontal position when the ring rail moves up to its normal lowest position, and therefore side bars 8 are returned to the position with respect to support 4 as illustrated by Figs. 1 and 2.

It is pointed out that the improvement according to the present invention is especially advantageous in the case of spinning machines the spindles of which are located very close to one another.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A spinning machine which comprises, in combina-

tion, a frame, a plurality of parallel spindles rotatably mounted on said frame, a ring rail structure slidable in said frame in a direction parallel to said spindles, said structure having a normal reciprocating movement of given amplitude in said direction and a supplementary underwinding stroke beyond said amplitude, guides for the yarns wound on said spindles respectively, arms carrying said guides movably mounted on said ring rail structure for retraction of said guides from their positions in line with said spindles respectively, and cooperating means respectively carried in fixed position by said frame and movably guided by said ring rail structure for automatically actuating said arms to retract said yarn guides in response to the movement of said structure beyond its normal amplitude to perform said supplementary underwinding stroke.

2. A spinning machine which comprises, in combination, a frame, a plurality of parallel spindles rotatably mounted on said frame, a ring rail structure slidable in said frame in a direction parallel to said spindles, said structure having a normal reciprocating movement of given amplitude in said direction and a supplementary underwinding stroke beyond said amplitude, guides for the yarns wound on said spindles respectively, arms car-

rying said guides pivoted to said ring rail structure about axes at right angles to said spindles to permit retraction of said guides from their positions in line with said spindles respectively, side bars guided on said ring rail structure slidably in a direction parallel to said spindles, and fixed parts carried by said frame to engage said side bars when said ring rail structure is having said supplementary underwinding stroke, said side bars being so positioned with respect to said ring rail structure as to engage said arms and pivot them upwardly when said fixed parts engage said side bars.

5 3. A spinning machine according to claim 2 in which, in the retracted position of said yarn guides, said arms are obliquely disposed so that when said arms are no longer acted upon they return to horizontal position under the mere action of gravity.
